(57) **CLAIM**

The ornamental design for a headgear, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front, top and right side perspective view of a headgear, in an as-worn configuration, embodying our new design.

FIG. 2 is a rear, bottom and left side perspective view thereof.

FIG. 3 is a front view thereof.

FIG. 4 is a rear view thereof.

FIG. 5 is a right side view thereof.

FIG. 6 is a left side view thereof.

FIG. 7 is a top view thereof.

FIG. 8 is a bottom view thereof.

FIG. 9 is an enlarged view of a portion IX of a headgear having a weld pattern, embodying our new design.

FIG. 10 is an enlarged perspective view thereof.

FIG. 11 is an enlarged view of a portion XI of a headgear having a weld pattern, embodying our new design.

FIG. 12 is an enlarged perspective view thereof.

FIG. 13 is an enlarged view of a portion XIII of a headgear having a weld pattern, embodying our new design.

FIG. 14 is an enlarged perspective view thereof.

FIG. 15 is an enlarged view of a portion XV of a headgear having a weld pattern, embodying our new design.

FIG. 16 is an enlarged perspective view thereof.

FIG. 17 is an enlarged front, top and right side perspective view of the headgear of FIGS. 1-16, in an as-worn configuration, embodying our new design.

FIG. 18 is a rear, bottom and left side perspective view thereof.

FIG. 19 is a front view thereof.

FIG. 20 is a rear view thereof.

FIG. 21 is a right side view thereof.

FIG. 22 is a left side view thereof.

FIG. 23 is a top view thereof; and,

FIG. 24 is a bottom view thereof.

The broken lines in the drawings illustrate portions of the headgear which form no part of the claimed design.

1 Claim, 18 Drawing Sheets
